INVENTOR.
Herbert C. Landon.
BY William J. Jackson.
ATTORNEY.

UNITED STATES PATENT OFFICE.

HERBERT C. LANDON, OF WEST NEW YORK, NEW JERSEY, ASSIGNOR TO ALVAH BUSHNELL COMPANY, OF PHILADELPHIA, PENNSYLVANIA.

TEMPORARY BINDER.

Application filed June 1, 1921. Serial No. 474,197.

To all whom it may concern:

Be it known that I, HERBERT C. LANDON, a citizen of the United States, residing at West New York, county of Hudson, and 5 State of New Jersey, have invented certain new and useful Improvements in Temporary Binders, of which the following is a specification.

This invention relates to that type of 10 binder in which letters or other loose leaf documents and papers may be temporarily filed.

The leading object of the present invention is to provide a binder of this character 15 which is of light and durable construction of few and simple parts and of comparatively inexpensive structure. A further object relates to the provision of general details of construction and in the arrangement 20 and combination of parts for attaining the results contemplated by the leading object.

The invention consists of the improvements hereinafter described and finally claimed.

25 The nature, characteristic features and scope of the invention will be more fully understood from the following description taken in connection with the accompanying drawings forming part hereof, and in 30 which:

Fig. 1, is a view of a binder embodying features of the present invention, open to receive leaves.

Fig. 2, is an edge view thereof, and

35 Fig. 3, is a view in central section, drawn to an enlarged scale of one of the leaf retaining devices shown in Figs. 1 and 2.

For the purpose of illustrating my invention I have shown in the accompanying 40 drawings one form thereof which is at present preferred by me, since the same has been found in practice to give satisfactory and reliable results, although it is to be understood that the various instrumentalities 45 of which my invention consists can be variously arranged and organized and that my invention is not limited to the precise arrangement and organization of the instrumentalities as herein shown and described.

50 In the drawings 10 designates a pair of backs of suitable material. In practice press-board or other stiff material has been found to give excellent results. The backs are connected by a portion 11 of pliable material as linen, muslin or equivalent ma-

terial. Secured to the inner face of portion 11, as by rivets 12 or equivalent mediums, are spaced, elongated plates 13, of thin metal, which plates are slightly curved, longitudinally considered, to conform to the 60 shape of portion 11. One end of each plate is bent upwardly as at 14 and outwardly upon a curved line as at 15. The part 14 is apertured as at 16 for a purpose to presently appear. The opposite end of each plate is 65 bent upwardly as at 17, curved outwardly as at 18 and then bent downwardly as at 19. The parts 17 and 19 are spaced apart as at 20 and the part 17 is apertured as at 21 which aperture is in alignment with 70 aperture 16. Complemental to each plate is an impaling pin 22 having a head 23. In practice conventional wire nails are efficient for the purpose. I prefer, however, to cut off the nail points. The pins are 75 passed through the apertures 21 prior to the parts 19 of the plates 13 being turned over. The heads 23 serve to prevent undue longitudinal movement of the pins yet there is sufficient play between the parts to permit 80 movement of the pins in angular directions. In locked position of each pin the free end thereof is seated within aperture 16. In practice the parts 14—15 of a plate is sufficiently yielding so that a pin 22 when 85 pressed there-against serves to move said parts outwardly so that said pin may be snapped to place in aperture 16. In Fig. 2, the pin is out of engagement with aperture 16 and in Fig. 3 the pin is locked in place. 90 In practice loose leaves (not shown) and preferably, though not essentially, provided with eyelet openings, are impaled upon the pins 22, while in the position shown in Fig. 2, and then said pins are snapped to closed 95 position. A securing device comprises only two parts thus ensuring cheapness and simplicity. It may be stated that a pin 22 has in effect a universal joint connection with a part 17 thus insuring the movement 100 thereof to readily accept loose leaves.

It will now be apparent that I have devised a novel and useful construction which embodies the features of advantage enumerated as desirable in the statement of the 105 invention and the above description and while I have in the present instance shown and described the preferred embodiment thereof which has been found in practice to give satisfactory and reliable results, it 110

is to be understood that the same is susceptible of modification in various particulars without departing from the spirit or scope of the invention or sacrificing any of its advantages.

What I claim is:

In a temporary binder the combination of a pair of backs and a connecting portion, a plate one end of which is provided with 10 an upwardly extended, apertured part bent over, extended downwardly in parallelism with and spaced throughout its extent from said apertured part, the other end of which plate is bent upwardly, is apertured in 15 alignment with the first mentioned aper-

ture and is thereafter outwardly and upwardly extended in a curved manner, the intermediate portion of said plate being secured to said connecting portion of the binder, and an impaling-pin passing 20 through the first mentioned aperture for engagement with the second mentioned aperture which pin has a disc-like head freely arranged within the space formed by the upwardly and downwardly extended parts 25 of the plate to provide a universal joint connection for said pin.

In testimony whereof, I have hereunto signed my name.

HERBERT C. LANDON.
